(57) **CLAIM**

The ornamental design for a lamp, as shown and described.

DESCRIPTION

1. Lamp
- 1.1 : Perspective
- 1.2 : Perspective
- 1.3 : Bottom
- 1.4 : Top
- 1.5 : Right
- 1.6 : Front

The broken lines shown in the figures illustrate portions of the lamp which form no part of the claimed design; the break lines shown in FIGS. 1.1, 1.2, 1.5, and 1.6 indicate that the appearance of any portion of the lamp between the break lines forms no part of the claimed design.
